[57] CLAIM

The ornamental design for an animal restrainer, as shown.

DESCRIPTION

FIG. 1 is a top plan view of an animal restrainer showing my new design;

FIG. 2 is an elevational view taken from one side thereof;

FIG. 3 is an elevational view taken from one end thereof;

FIG. 4 is a bottom plan view thereof;

FIG. 5 is an elevational view taken from the end opposite that shown in FIG. 3; and

FIG. 6 is an elevational view taken from the side opposite that shown in FIG. 2.
